US00D930009S

(12) **United States Design Patent** (10) **Patent No.:** **US D930,009 S**
Karunamuni et al. (45) **Date of Patent:** **** Sep. 7, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Chanaka Karunamuni**, San Jose, CA (US); **Stephen O. Lemay**, Palo Alto, CA (US); **Marcel van Os**, Santa Cruz, CA (US)

(73) Assignee: **Apple Inc.**, Cupertino, CA (US)

(**) Term: **15 Years**

(21) Appl. No.: **29/711,971**

(22) Filed: **Nov. 4, 2019**

Related U.S. Application Data

(63) Continuation of application No. 29/588,770, filed on Dec. 22, 2016, now abandoned, which is a continuation of application No. 29/540,719, filed on Sep. 27, 2015, now Pat. No. Des. 775,149, which is a continuation of application No. 29/495,064, filed on Jun. 26, 2014, now Pat. No. Des. 740,845, which is a continuation of application No. 29/424,281, filed on Jun. 10, 2012, now Pat. No. Des. 711,911.

(57)

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
